TAPE REEL RACK

David Wright, Shrewsbury, Mass. (% Barry Wright Corporation, 160 Gold Star Blvd., Worcester, Mass. 01606)

Filed Oct. 2, 1972, Ser. No. 294,153

Term of patent 14 years

Int. Cl. D6—04

U.S. Cl. D6—188

FIG. 1 is a perspective view of a tape reel rack showing my new design;

FIG. 2 is an end elevational view; and

FIG. 3 is a bottom plan view.

I claim:

The ornamental design for a tape reel rack, as shown.
